UNITED STATES PATENT OFFICE

2,583,758

SICKLE GRINDER

Clifford B. Webber, Coon Rapids, Iowa

Application January 30, 1946, Serial No. 644,243

5 Claims. (Cl. 51—36)

1

My invention relates to improvements in sickle grinders, an object thereof being to provide a simple, durable, inexpensive and easily operated grinder capable of accurately sharpening the blades of sickles of the type commonly employed in mowers and reapers.

A sickle of the type mentioned consists of a bar and a series of generally triangular blades arranged in edgewise abutting relationship and riveted at the butts thereof upon said bar. The forwardly pointing body of each blade is beveled along the opposite upper margins thereof to produce sharp edges. In use, sickles rapidly become dull necessitating the resharpening thereof in some manner, it being preferable that the blades be ground in their assembled dispositions on the sickle-bar, whereby the sickle may remain undisturbed and ready for prompt reapplication to the implement in which it is used. This mode of sharpening sickle blades is common and is customarily carried out by the employment of a grinding wheel of opposed frusto-conical formation having oppositely beveled faces against which adjacent edges of adjacent blades of a sickle are concurrently presented with the crotch between such blades receiving the ridge on the grinding wheel. Conventional manipulation of a sickle relative to a grinding wheel, whereby the blades of the sickle are successively presented to said wheel and moved back and forth thereover, results in the sharpening of the blades in a more or less satisfactory manner depending upon the effort involved and the accuracy of manipulation of the sickle. Mechanical contrivances of different kinds have been employed with limited success in so handling a sickle assembly, but all of them, so far as known, are relatively complicated and difficult to operate reliably, especially in the hands of inexperienced persons.

One of the objects of the present invention is to provide a sickle grinder constructed to overcome the disadvantages experienced in previous grinders, a more specific object being to provide a sickle grinder, as aforesaid, in which the sickle is stationarily held while the grinding wheel is moved relative thereto to sharpen the adjacent edges of adjacent blades of the sickle.

Another object of the invention is to provide in an instrument of present character a bed along which a sickle may be advanced, step by step, successively to bring the blades thereof within range of the grinding wheel, a further object being to supply yielding means for releasably holding a sickle in place upon said bed, and an additional object being to provide means for guiding

2

the operator in appropriately stationing the sickle on the bed at each step thereof in the grinding operation.

Another object of the invention is to provide simple and effective mounting means for the grinding wheel which is normally self-disposed to present said grinding wheel near the position wherein the grinding of a sickle is to be effected thereby, and which is readily movable to bring the grinding wheel into grinding contact with the sickle at each step in the sharpening thereof.

A further object of the invention is to provide a grinder of the instant nature in which the prime mover for the grinding wheel is supported together with said wheel by the movable mounting means for said wheel.

Other objects of the invention reside in the novel combination and arrangement of parts and in the details of construction hereinafter illustrated and/or described.

In the drawings, Fig. 1 is a perspective view of a form of sickle grinder embodying my invention; Fig. 2 is a side elevational view of the structure illustrated in Fig. 1, a sickle being shown in place on the bed rail of the device; Fig. 3 is a plan view and Fig. 4 is a front elevational view of the structure illustrated in Fig. 1.

Reference being had to the drawings wherein similar parts are designated by similar reference characters throughout the several views, it will be seen that the illustrated embodiment of my invention includes a frame A consisting of a rearwardly opening channel-bar constituting a bed rail *a*, and a tubular member intermediately bent to form a post *10* and a forwardly extending beam *11*. Another tubular frame member, forming a tie-reach *12* between said post *10* and said bed-rail *a*, is welded at its rear end to said post *10*, in parallelism with the beam *11*, and is welded at its front end to the bed rail *a* intermediately of said rail. The bed rail *a* is disposed at right angles to the upright plane common to said tie-reach *12* and beam *11* and the channel in said bed-rail receives the said front end of said tie-reach *12*. Welded to the base of the post *10* is a foot-plate *13* which, together with the lower flange *14* of the bed-rail *a*, provides a footing for the frame A, as on a bench or table *15*, or other suitable supporting structure. Placed on a bench or table, the frame A will preferably be anchored thereto as by screws *16*.

A hanger B, slung from the beam *11*, comprises an elongated mounting *b*, a link *b'* depending from the beam *11* and supporting said mounting member *b* at the rear thereof, and a link *b''* de-

pending from said beam 11 and supporting said mounting b at the front thereof. The body of the mounting, as shown, is an angle-bar 17, one flange thereof being substantially horizontally disposed and the other flange vertically disposed. Welded edgewise along the free edge of said horizontal flange is a plate or shelf 18.

The body of the rear hanger link b' consists of a channel-bar 19 to the lower end of which a clevis 20 is welded. A pivot pin 21 extending through the arms of said clevis 20 also extends through a bushing 22 welded to the rear end of the angle-bar 17. A similar clevis 23 is swivelly connected to the beam 11 by means of a stud 24 extending upwardly through said beam and fitted at its upper end with a nut 25 riding the top of the beam 11. A pivot pin 26 extending through the depending arms of said clevis 23 also extends through a bushing 27 welded to the upper end of the channel-bar 19.

The body of the front hanger link b² comprises a helical extension spring 28 which is caught at its upper end on a hook 29 hung from the rail 11 and which is caught at its lower end on an up-standing hook 30 welded to the front portion of the angle-bar 17.

A horizontally disposed journal bearing 31, welded to the front end of said angle-bar 17, revolvably supports a shaft 32. Fitted to said shaft 32 near one end of the bearing 31, is a grinding wheel 33 of opposed frusto-conical formation, the same having an intermediate annular ridge 34 and sloping faces 35 at either side thereof. Near the other end of said bearing 31, a pulley 36 is secured to said shaft 32, said pulley 36 being connected by a belt 37 to the pulley 38 of an electric motor 39 bolted to the angle bar 17 and shelf 18 of the hanger mounting b between the front and rear suspension links b¹, b² therefor.

In the position of the hanger B, normally assumed by gravity, the grinding wheel 33 is axially disposed in parallelism with the bed rail a and the lowermost point of said wheel rests slightly above a point substantially mid-width of the upper flange 40 of the bed rail intermediate the ends of said rail.

A sickle C with blades 41 riveted to a bar 42, is placed on the bed rail a in the illustrated manner in which the under faces of the blades 41 rest upon the upper flange 40 of said bed rail a with the blades 41 pointing rearwardly of the device and the rearward edge of the bar 42 abutting against the web 43 of the bed rail a at the front thereof. Being thus disposed relative to said bed rail, the sickle C is slidably guided thereby for longitudinal movement lengthwise thereof.

Welded to the mounting b of the hanger B is a forwardly extending arm 44 formed at its free end to provide a handle 45. Grasping said handle 45, an operator can depress the forward end of the mounting b and swing the same fore and aft to bring the grinding wheel 33 movably into engagement with the sickle. Appropriately, the sickle will be stationed on the bed rail a so that the crotch between two adjacent blades 41 will be centered in the normal vertical plane of the annular ridge 34 of the grinding wheel 33. Thus, in a simple downward movement of the handle 45 followed by a forth and back motion, the sloping surfaces 35 of the grinding wheel 33 will be movably contacted with the beveled margins of such two adjacent blades similarly to grind and sharpen the edges thereof. Having ground said edges as desired, the operator will release the handle 45 and the spring 28, which was pre-

5 viously extended in depressing the forward end of the mounting b, will contract and return said end of said mounting to its normal elevated position clearing the grinding wheel 33 from the sickle blades.

10 The upper flange 40 of the bed rail a is notched, as at 46, to accommodate the lower portion of the grinding wheel 33 which extends downwardly beneath the plane of the sickle blades 41 in the grinding operation. A guard 47, welded to the mounting b and overreaching the upper portion of the grinding wheel 33 protects the operator from flying sparks emanating from said grinding wheel.

15 The sickle being ground is shifted step by step along the bed rail successively to present adjacent edges of adjacent blades 41 in position to be engaged by the grinding wheel 33. To keep the rear edge of the sickle bar 42 in slidably guided relationship against the front face of the web 43 of the bed rail a, a front guide 48 is provided. Said front guide 48 consists of a clip welded to said web 43 of the bed rail a. This clip has an upstanding terminal flange 49 which is engaged by the front edge of the sickle bar 42. On said flange 49 of the guide-clip 48 is an indicator-line 50 with which joints between adjacent blades 41 are successively registered in the step by step advance of the sickle C along the bed rail a. In registering the joint between two adjacent blades 41 with said indicator-line 50, the crotch between two other adjacent blades 41 will be substantially centered with respect to the normal plane of the annular ridge 34 of the grinding wheel 33. The sickle C, thus stationed with reference to the indicator 50, will be properly contacted by the grinding wheel 33 upon maneuvering the hanger b, as aforesaid. Preferably, the grinding wheel 33 rotates in a clockwise direction as seen in Fig. 2, the tendency of the sickle to creep rearwardly across the bed rail a being resisted by engagement of the sickle bar 42 with the front face of the web 43 of said bed rail. To hold the sickle C in endwise adjusted position on top of the bed rail a, I provide a releasable clamp D including a hold-down finger 51 disposed above the upper face of the bed rail a near the front guide 48 aforesaid. Said finger 51 is pivoted at its rear end, as at 52, to the rear end of a rearwardly extending mounting strip 53 fastened to said bed rail a. Encircling the upper portion of a headed bolt 54, extending upwardly through said mounting strip 53 and hold-down finger 51, is a helical spring 55 which is compressed between said finger 51 and a nut 56 on said bolt 54. Through this bolt 54, said spring 55 yieldingly reacts to clamp the hold-down finger 51 against the upper face of sickle C on the bed rail a, and, in turn, to clamp such sickle against said bed rail. Said clamp D is released to free its grip upon the sickle simply by lifting the forward end of the hold-down finger 51 against the action of the spring 55. If desired, a second or supplementary front guide, similar to said front guide 48, may be secured to the bed rail a near the end thereof opposite the clamp D.

20 25 30 35 40 45 50 55 60 65 70 75 While the rear suspension link b' confines the hanger mounting b substantially to a forward and backward motion, the swiveling of said link, at its connection with the beam 11, frees the front end of the hanger mounting b for sidewise movement permitted by the spring 28 in the front suspension link b². Thus, considerable tolerance is provided, whereby the adjacent edges of adjacent blades of a sickle may be similarly and uniformly ground even though the crotch be-

tween such blades is not precisely centered relative to the ridge 34 of the grinding wheel 33. Having this tolerance, the grinding wheel, upon being depressed, seeks its seat on the two blades, shifting one way or the other lengthwise of the sickle to center the wheel relative to said blades. This feature enables the device to perform effectively notwithstanding irregularities in the construction of a sickle or misadjustment thereof on the bed rail *a*, or lack of skill on the part of the operator.

From the foregoing, it will be readily comprehended that the instant device is simple, compact, durable and inexpensive in construction and, while relatively rough in construction, is capable of operating with precision in unskilled hands. A feature facilitating the use of the device resides in the stability of the swinging hanger *B* by reason of the added weight on the hanger mounting *b* supplied by the motor 39 for driving the grinding wheel 33.

Changes in the specific form of my invention, as herein described, may be made within the scope of what is claimed without departing from the spirit of my invention.

Having described my invention, what I claim as new and desire to protect by Letters Patent is:

1. A grinder comprising a frame having an overhead support, a first suspension linkage hung from said support adjacent its forward end thereof, said suspension linkage including a yieldingly extensible element constructed and arranged to permit both fore and aft and lateral swinging of the lower end of said first linkage, a second suspension linkage hung from said support adjacent its rear end thereof, said second linkage comprising a swiveling element connected at one end to said overhead support for rotation about a vertical axis, an arm pivotally connected at one end to the opposite end of said swiveling element for movement about a horizontal axis, a hanger support pivotally connected adjacent one end thereof to the free end of said arm for movement about a horizontal axis, the hanger support being connected to said first suspension linkage adjacent its forward end thereof, a grinding wheel revolvably supported on said hanger support adjacent its forward end thereof, a motor mounted on said hanger support between said first and second linkages, and means operatively connecting said motor to said grinding wheel for rotating the same, whereby the first suspension linkage permits the forward end of the hanger support to be moved downwardly and to be swung fore and aft and sidewise to place said grinding wheel in contact with the surfaces to be ground and said second suspension linkage permits the rear end of said hanger support to turn about the vertical axis of rotation of said swiveling element conformably with the sidewise swinging movements of the forward end of said hanger support and further permits the hanger support to pivot back and forth conformably with fore and aft swinging movements of the forward end of said hanger support.

2. A grinder comprising a frame having an overhead support, a first suspension linkage including a helical spring hung from said support adjacent its forward end thereof, a second suspension linkage hung from said support adjacent its rear end thereof, said second linkage comprising a stud connected at one end to said overhead support for rotation about a vertical axis, the opposite end of said stud connected to a U-shaped member, an arm pivotally connected at one end

within the legs of said U-shaped member for movement about a horizontal axis, a hanger support pivotally connected adjacent one end thereof to the free end of said arm for movement about a horizontal axis, the hanger support being connected to said first suspension linkage adjacent its forward end thereof, a grinding wheel revolvably supported on said hanger support adjacent its forward end thereof, a motor mounted on said hanger support between said first and second linkages, and means operatively connecting said motor to said grinding wheel for rotating the same, whereby the first suspension linkage permits the forward end of the hanger support to be moved downwardly and to be swung fore and aft and sidewise to place said grinding wheel in contact with the surfaces to be ground and said second suspension linkage permits the rear end of said hanger support to turn about the vertical axis of rotation of said swiveling element conformably with the sidewise swinging movements of the forward end of said hanger support and further permits the hanger support to pivot back and forth conformably with fore and aft swinging movements of the forward end of said hanger support.

3. A grinder for a sickle consisting of a bar and a series of triangular tooth-like blades secured at their butts upon said bar and bevelled along their free upper margins to provide cutting edges, said grinder comprising a holder for the sickle, a frame having an overhead support, a first suspension linkage hung from said support adjacent its forward end thereof, said suspension linkage including a yieldingly extensible element constructed and arranged to permit both fore and aft and lateral swinging of the lower end of said first linkage, a second suspension linkage hung from said support adjacent its rear end thereof, said second linkage comprising a swiveling element connected at one end to said overhead support for rotation about a vertical axis, an arm pivotally connected at one end to the opposite end of said swiveling element for movement about a horizontal axis, a hanger support pivotally connected adjacent one end thereof to the free end of said arm for movement about a horizontal axis, the hanger support being connected to said first suspension linkage adjacent its forward end thereof, a grinding wheel of opposed frustoconical formation having dual grinding surfaces, said grinding wheel being revolvably supported on said hanger support forwardly thereof above said holder, a motor supported on said hanger support between said first and second linkages, and means operatively connecting said motor to said grinding wheel for rotating the same, whereby the first suspension linkage permits the forward end of the hanger support to be moved downwardly and to be swung fore and aft and sidewise to contact the two opposing faces of the grinding wheel simultaneously with and along adjacent edges of two adjacent blades of the sickle, and said second suspension linkage permits the rear end of said hanger support to turn about the vertical axis of rotation of said swiveling element conformably with the sidewise swinging movements of the forward end of said hanger support and further permits the hanger support to pivot back and forth conformably with fore and aft swinging movements of the forward end of said hanger support.

4. A grinder for a sickle consisting of a bar and a series of triangular tooth-like blades secured at their butts upon said bar and bevelled

along their free upper margins to provide cutting edges, said grinder comprising a holder for the sickle, a frame having an overhead support, a first suspension linkage including a helical spring hung from said support adjacent its forward end thereof, a second suspension linkage hung from said support adjacent its rear end thereof, said second linkage comprising a stud connected at one end to said overhead support for rotation about a vertical axis, a U-shaped member connected to the opposite end of said stud, an arm pivotally connected at one end within the legs of said U-shaped member for movement about a horizontal axis, a hanger support pivotally connected adjacent one end thereof to the free end of said arm for movement about a horizontal axis, the hanger support being connected to said first suspension linkage adjacent its forward end thereof, a grinding wheel of opposed frustoconical formation having dual grinding surfaces, said grinding wheel being revolvably supported on said hanger support forwardly thereof above said holder, a motor mounted on said hanger support between said first and second linkages, means operatively connecting said motor to said grinding wheel for rotating the same, whereby the first suspension linkage permits the forward end of the hanger support to be moved downwardly and to be swung fore and aft and sidewise to contact the two opposing faces of the grinding wheel simultaneously with and along adjacent edges of two adjacent blades of the sickle and said second linkage permits the rear end of said hanger support to turn about the vertical axis of rotation of said swiveling element conformably with the sidewise swinging movements of the forward end of said hanger support and further permits the hanger support to pivot back and forth conformably with fore and aft swinging movements of the forward end of said hanger support.

5. A grinder comprising a frame having an overhead support, a first pendulous suspension linkage hung from said support forwardly thereof, a second pendulous suspension linkage hung from said support rearwardly thereof, a hanger support carried by said first and second linkages, said first linkage being connected at its

lower portion to said hanger support forwardly thereof and said second linkage being connected at its lower portion to said hanger support rearwardly thereof, a grinding wheel revolvably supported on the hanger support at the forward portion thereof, a motor mounted on said hanger support between said first linkage and said second linkage, means operatively connecting said motor to said grinding wheel for rotating the same, said first linkage being yieldingly extensible enabling the forward portion of the hanger support to be forcedly moved downwardly to lower the grinding wheel into contact with an article to be ground, said first linkage being swingable fore and aft and laterally enabling said forward portion of said hanger support to be similarly moved for shifting the grinding wheel forwardly, rearwardly and sidewise, said second linkage being swingable, but only fore and aft, enabling the rearward portion of said hanger support to move conformably with the forward and rearward movements of said forward portion of said hanger support while depriving said rearward portion of said hanger support of lateral swinging movements, said second linkage supporting said rearward portion of said hanger support swivelly enabling the same to turn horizontally in conformity with the sidewise movements of said forward portion of said hanger support.
